UNITED STATES PATENT OFFICE.

LUDOVIC MARCQ, OF BOULOGNE, FRANCE.

FIREARM.

1,372,763.

Specification of Letters Patent. Patented Mar. 29, 1921.

Application filed April 10, 1920. Serial No. 372,895.

To all whom it may concern:

Be it known that I, LUDOVIC MARCQ, a citizen of France, residing at Boulogne-sur-Mer, in Pas-de-Calais, France, have invented certain new and useful Improvements in Fire-
10 arms; and I do hereby declare the following to be a full, clear, and exact description of the invention, such as will enable others skilled in the art to which it appertains to make and use the same.

This invention relates to fire arms and more particularly to fire arms which are held in the hand and commonly known as pistols or revolvers, but in so specifying 15 the particular fire arms to which I prefer to apply my invention, it is not to be understood that I restrict myself thereto. The invention is equally applicable to other fire arms, such as rifles, shot guns and so forth.

20 The objects of the invention are to provide a fire arm with which accurate aim may be taken; to avoid disturbing the aim when the trigger is actuated; to adapt the device to ready application to fire arms as heretofore constructed; to obtain positiveness of action and control; to secure simplicity of construction and operation, and to obtain other advantages and results as may be brought out in the following description.

25 Referring to the accompanying drawing in which like numerals of reference indicate similar parts throughout the several views, Figure 1 is a side elevation of a fire arm embodying my invention;

30 Fig. 2 is a rear view of the same; Fig. 3 is a rear view showing the same in use; Fig. 4 is a longitudinal sectional view; and Fig. 5 is a cross sectional view on line 5—5
35 of Fig. 1.

In the specific embodiment of the invention illustrated in said drawing, the reference numeral 1 indicates the barrel of the fire arm and 2 represents the stock by which 45 the fire arm is usually grasped. At the side of the barrel is positioned a guide 3, disposed parallel to the axis of the barrel adjacent thereto and at an elevation such as to bring the operator's finger when placed in said 50 guide at the same level as the barrel. The guide is so arranged that the operator in holding the fire arm rests his index finger in the guide, and as a person can and does accurately and instinctively point at an object with his index finger, the fire arm will 55 thus be as accurately and instinctively

aimed. This obviously is of great advantage, as it does not require extended practice and experience to become a marksman by use of the present invention.

While the actual construction of guide may be varied, for illustrative purposes I have shown the same of one piece having a finger-receiving portion 4 adapted to be positioned at the side of the barrel and having a base portion 5 extending laterally inward under the barrel for attaching the guide to the barrel. The barrel is shown as provided with a dove-tail tongue 6 extending longitudinally of, and integral with the barrel, and the base portion 5 of the guide has a corresponding groove 7 by which the guide may be supported from the barrel. The base portion of the guide is also provided with one or more slots 8 extending longitudinally thereof, through which pass screws 9 which enter the solid part of the barrel and hold the guide in proper position. By virtue of the slots 8, the guide may be adjusted longitudinally of the barrel to accord to different sizes of fingers, but after the purchaser sets the guide to fit, he does not change it.

As a further feature of my invention, I provide means for actuating the trigger without disturbing the index finger. This is important, for where the finger next the index finger is wiggled to actuate the trigger, the index finger is likely to be deflected slightly. Obviously even a slight disturbance of the index finger will deviate the barrel from its true direction, and result in the shot missing its mark. In my invention, I employ the thumb for actuating the trigger, and for this purpose I provide a trigger 10 at the side of the firearm which in set position projects substantially perpendicularly therefrom in the proximity of the operator's thumb, as shown in full lines in Fig. 3, so as to be readily depressed as shown in dotted lines for releasing the hammer and shooting the gun.

For purposes of illustrating a complete and operative mechanism, I have shown the inner end of the lever adapted to engage under a trip bar 11 which has a notch 12 for receiving a lug 13 on hammer 14. Said lug engaged in said notch holds the hammer in retracted or cocked position, and depression of the trigger will operate to release said lug and permit the hammer to slide under the impetus derived from suitable means such as compression spring 15, and strike

the cap of cartridge 16. It is to be understood, however, that the structure of hammer and its control from the trigger may be widely varied, and in fact may be an adaptation of the usual hammer construction of any of the hammer mechanisms to be found in firearms now on the market, to render it operative from a trigger arranged and constructed in accordance with my invention.

Furthermore, it is to be understood that other mechanical equivalents, modifications and changes may be made in the details of construction of my improved fire arm without departing from the spirit or scope of the invention as set forth in the following claims when construed in the light of the prior art.

Having thus described the invention, I claim:—

1. A firearm having a hammer and a barrel, a finger receiving member at one side of the barrel and a trigger projecting from the other side of said firearm for engaging the hammer, whereby the trigger may be actuated by the thumb of the hand holding the firearm to release the hammer without disturbing the finger engaging the finger receiving member.

2. A firearm having a hammer and a

barrel, a finger receiving member at one side of the barrel, a base for the finger receiving member extending beneath the barrel, means for adjustably securing the base to the barrel, and a trigger projecting from the side of said fire arm for releasing the hammer whereby the trigger may be actuated by the thumb of the hand holding the fire arm without disturbing the finger engaging the finger receiving member.

3. A fire arm having a barrel, a finger receiving member at one side of the barrel, a base on the finger receiving member extending beneath the barrel and provided with a groove, a tongue formed on the barrel and disposed within said groove whereby to provide adjustment for the base and means for retaining said base in various adjusted positions.

4. A fire arm having a barrel, a finger receiving member at one side of the barrel, a base for said member extending beneath the barrel and adjustably mounted beneath the barrel, said base having slots therein and set screws arranged within the slots and engaging the barrel whereby said base will be retained in an adjusted position.

In testimony whereof I affix my signature.
LUDOVIC MARCQ.
